(No Model.)

D. W. WARNOCK.

COMBINATION TOOL FOR SQUARING, LEVELING, &c.

No. 359,372.

Patented Mar. 15, 1887.

UNITED STATES PATENT OFFICE.

DAVID WESLEY WARNOCK, OF LEXINGTON, KENTUCKY.

COMBINATION-TOOL FOR SQUARING, LEVELING, &c.

SPECIFICATION forming part of Letters Patent No. 359,372, dated March 15, 1887.

Application filed February 18, 1886. Serial No. 192,349. (No model.)

To all whom it may concern:

Be it known that I, DAVID WESLEY WARNOCK, of Lexington, in the county of Fayette and State of Kentucky, have invented a new and useful Improvement in Combination-Tools, of which the following is a specification, reference being had to the annexed drawings, forming a part thereof, in which—

Figure 1 is a side elevation. Fig. 2 is a side elevation with the side of the body of the tool removed. Fig. 3 is a detail view showing the compasses in position for use. Fig. 4 is a transverse section taken on line *x x* in Fig. 1. Fig. 5 is a section taken on line *y y* in Fig. 4.

15 Similar letters of reference indicate corresponding parts in the different figures of the drawings.

The object of my invention is to provide a combination-tool for squaring, leveling, plumb-ing, centering cylinders, laying off angles, starting a saw-kerf for cutting a key-hole, and for cutting lace-leathers for belting.

20 My invention consists in various instrumen-talities by which these objects are attained, as hereinafter more fully described.

The body *A* of the combination-tool is pro-25 vided with a longitudinal groove, *a*, in one edge thereof, and to one end of the body and in the longitudinal groove is secured the square blade *B*, which is cut away at an angle of forty-five 30 degrees upon its inner edge near the body *A*, forming a beveled shoulder, *a'*, for receiving and supporting the end of a slotted bar, *C*, when in the position shown in dotted lines, 35 Fig. 1. The bar *C* is fitted to the slot of the body and is provided with a pivotal pin, *b*, which projects through a slot, *c*, formed in the side of the body, and retains the bar *C* in the body *A*, while admitting of adjusting it in po-40 sition for use, or folding it into the body *A* when not in use. The end of the slot *c* nearest the blade *B* is curved toward the blade, and the opposite end of the slot is provided with a branch, *d*.

45 In the groove *a* of the body of the instru-ment is placed a thin pair of compasses, *D*, with a pivotal pin, *e*, projecting through the slot *c* in the side of the body *A*. When it is desired to use the bar *C*, the compasses *D* are 50 drawn forward in the slot into the branch *d* and the pivotal pin of the bar *C* is moved for-

ward to the extremity of the slot *c*, beyond the branch *d*, when the pivot of the compasses may be moved back into the slot *c* and the compasses may be pushed back entirely within 55 the body *A*.

When the bar *C* is folded over upon the shoulder *a'*, as shown in dotted lines 1, Fig. 1, a left miter can be obtained; and when the bar has been pushed back in the slot *c* to the angle 6c of the body and blade and then inclined out-ward at an angle of forty-five degrees, as shown in dotted lines 2, said figure, a right miter can be obtained. By this construction both right and left miters can be obtained without re- 65 versing or turning the square over.

In the body *A* is formed a cavity, into which the protractor *E* may be turned when not in use. The outer edge of the body *A* is pro-70 vided with a slot, *c'*, for receiving a key-hole saw, *F*, which is provided with a slot, *g*, in the wider end to receive a pin, *h*, passing through the body *A*, and at one end of the slot *g* is formed a notch, *i*, in which the pin *h* is received when the saw-blade is opened.

To facilitate the opening of the saw-blade, the back thereof is provided with a nick, *j*, for receiving the thumb-nail for lifting it out of the handle of the body *A*. In one side of the body, near the middle thereof, is secured 80 a spirit-level bulb, *G*, and to the end of the body *A*, at one side of the blade *B*, is secured a spirit-level bulb, *H*. The bulbs *G H* are employed for leveling and plumbing in the usual way.

85 The body *A* of the square also forms the body of the plumb and level.

In a transverse groove, *k*, formed in one side of the body *A*, is placed a steel bar, *l*, which is bent at right angles at its extremity 90 toward the blade *B*, and is formed into a knife, *m*, having a shank, *n*, which projects through a slot, *o*, in the blade *B*, and is provided with a nut, *p*, for clamping the bar *l* and knife *m* in any desired position along the length of the 95 slot *o*.

The knife *m* is designed for cutting lace-strings for belting, and is made adjustable to admit of cutting laces of different widths. When the knife *m* is not in use, it is moved 100 forward into a notch, *q*, in the edge of the body *A*.

Having thus described my invention, what I claim as new, and desire to secure by Letters Patent, is—

1. The combination of the body A, having slots *a c*, the blade B, provided with the beveled shoulder *a'*, and the slotted bar C, provided with the pivot *b*, substantially as herein shown and described.
2. A combination-tool consisting of the body A, having slots *a c*, the blade B, having the beveled shoulder *a'*, the slotted bar C, provided with the pivotal pin *b*, the compasses D, provided with the pivotal pin *e*, the protractor E, the spirit-level bulbs H G, and the bar *l*, carrying the lace-cutting knife *m*, substantially as herein shown and described.
3. A combination-tool consisting of the body A, having slots *a c c'*, the slotted bar C, having the pivotal pin *b*, the compasses D, provided with the pivotal pin *e*, the saw F, having the slot *g* and arranged to fold in the slot *c'* of the body A, the blade B, having the beveled shoulder *a'*, the folding protractor E, the adjustable lace-cutting knife *m*, and the spirit-level bulbs H G, secured in the end and side of the body A, substantially as herein shown and described.

DAVID WESLEY WARNOCK.
